UNITED STATES PATENT OFFICE

139,177

DESIGN FOR A COMBINED TOY TRUCK AND STAKE BODY TRAILER

Edith Hickling, Minneapolis, Minn.

Application May 15, 1944, Serial No. 113,592

Term of patent 7 years

(Cl. D34—15)

To all whom it may concern:

Be it known that I, Edith Hickling, a citizen of the United States, residing at Minneapolis, in the county of Hennepin and State of Minnesota, have invented a new, original, and ornamental Design for a Combined Toy Truck and Stake Body Trailer, of which the following is a specification, reference being had to the accompanying drawing, forming a part thereof.

Figure 1 is a side elevational view of a combined toy truck and stake body trailer showing my new design; and

I claim:

The ornamental design for a combined toy truck and stake body trailer, as shown.

EDITH HICKLING.
